ATTORNEYS.

UNITED STATES PATENT OFFICE.

JAMES F. GALLAGHER, OF BROOKLYN, NEW YORK.

DIAPHRAGM.

Application filed May 18, 1923. Serial No. 639,761.

To all whom it may concern:

Be it known that I, JAMES F. GALLAGHER, a citizen of the United States, residing in the borough of Brooklyn, of the city of New York, county of Kings, and State of New York, have invented certain new and useful Improvements in Diaphragms, of which the following is a specification.

My invention relates to an improvement 10 in pressure operated diaphragms and an object thereof is to provide a simplified construction which facilitates manufacture as well as repair and by which the tendency of the diaphragm to crystallize and break is 15 reduced to a minimum.

In the drawings,—

Fig. 1 shows my improved device in part 20 sectional elevation;

Fig. 2 is a section on the line 2—2 of Fig. 1; and

Fig. 3 is a section taken substantially on the line 3—3 of Fig. 2.

Referring to the drawings in detail,—1
1 designates a housing or casing adapted to
2 contain my improved diaphragm the hous-
ing being provided with a cap or cover 2.
The lower part of the housing is connected
3 in any suitable manner to a union 3 which
contains a valve to be controlled (not shown)
4 the valve stem 4 extending upwardly out of
the union and into the housing as I have
5 indicated. The upper end of the valve stem
is threaded or otherwise attached to the
lower section 5 of my improved diaphragm.

6 The diaphragm comprises a series of hol-
low thin walled diaphragm members 5, 6, 7,
8 and 9, as many of these members being
7 provided as may be desired and each mem-
ber being provided with spacing lugs S.
8 These diaphragm members are attached to
9 and in communication with each other
through the medium of flexible connections,
10 tubes 10, 11, 12 and 13 in the embodiment
illustrated, these tubes extending from a
11 point adjacent the periphery of one member
12 to a point at the periphery of the adjacent
13 member, the upper member 9 in addition
14 being provided with pipe 14 passing from
15 the top side thereof down through the hous-
ing 1 and into a coupling or union 15 which
16 communicates with a pipe 16 by which pres-
17 sure for operating the diaphragm is sup-
18 plied.

The lower diaphragm member 5 is pro-
19 vided on its under side with pins 17 and 18
20 receiving springs 19 and 20 employed for
the purpose of forcing the diaphragm mem-
bers upwardly against the action of the
21 pressure entering the diaphragm members
22 through the pipe 16.

23 It will be seen from the foregoing that
the diaphragm members 5, 6, 7, 8 and 9 are
24 connected to each other in a new and novel
manner which while permitting relative
25 movement between the diaphragm members
reduces the liability of crystallization of the
26 diaphragm members to a minimum but
27 should the connection of any one of the
28 connecting pipes 10, 11, 12, etc. to its corre-
29 sponding diaphragm members fracture it is
30 a simple matter to repair it.

31 I am aware that diaphragms have
32 heretofore been constructed of a plurality
33 of hollow members in communication with
34 each other such diaphragm members how-
35 ever being screw connected to each other at
36 their centers but inasmuch as the greatest
37 expansion of each diaphragm member takes
38 place at the center of the member these
39 screw connections are subjected to severe
40 bending stresses and soon crystallize and
41 break, whereas in my structure the ex-
42 pansion and contraction of the diaphragm mem-
43 bers is distributed over a wide area thereby
44 reducing the danger of crystallization and
45 breaking of the diaphragm to a minimum.

46 What I claim is:

47 In combination, a housing, a cap therefor,
48 a series of superimposed hollow diaphragm
49 members therein, flexible tubes attached to
50 the peripheries of said members and com-
51 municating with the interior thereof, a pres-
52 sure pipe communicating with one of said
53 diaphragm members, whereby there is pro-
54 vided a plurality of diaphragm members
55 connected in series to a pressure pipe, springs
56 attached to the periphery of the lower dia-
57 phragm member of the series for forcing
58 the diaphragm structure toward said cap,
59 and lugs for spacing said diaphragm
60 members.

61 This specification signed this 17th day of
62 May 1923.

JAMES F. GALLAGHER.
